UNITED STATES PATENT OFFICE

THOMAS PILLING, OF STALYBRIDGE, ENGLAND

STOP MOTION FOR LOOMS FOR WEAVING

Application filed December 4, 1929, Serial No. 411,548, and in Great Britain November 17, 1928.

This invention relates to improvements in stop motions for looms for weaving.

The object of the invention is to provide means whereby the loom is stopped just before the weft bobbin or cop is empty thereby obviating the necessity of turning back the loom to find the end after the weft has become exhausted or on the other hand of stopping the loom several picks before the weft has become exhausted which results in considerable waste of weft on the bobbin or cop.

According to the invention a coarse pitched screw is driven through friction gear from the take-up roller of the loom and a nut is mounted on the screw so that as the latter rotates it travels along the screw until a rod carried by the nut engages a stop adjustably mounted on a slide so that its position can be adjusted according to the length of the yarn on the bobbin or cop. In practice cops or bobbins of the same count of yarn are of approximately equal length so that when once the stop has been set for weaving a particular cloth it will not require to be re-set while the whole length of the cloth is being woven. The slide on which the adjustable stop is mounted carries an arm which is flexibly connected to the weft fork carrier so that when the rod on the nut engages the stop the movement of the slide tightens the flexible connection and causes the weft fork to remain in the path of the weft hammer and the weft lever to be operated to stop the loom. In order that the stop motion may be automatically reset to its original position after the loom has stopped, the end of the screw is mounted in a spring controlled bearing so that when the pressure on the bearing is released the friction driving gears will be disengaged and a spring which is gradually tightened as the screw rotates, will cause the latter to rotate in the opposite direction until the nut is returned to its starting position.

The invention will be described with reference to the accompanying drawings:

Fig. 1 is a side elevation showing the attachment on a loom.

Fig. 2 is a plan of same.

Fig. 3 is a side elevation.

Fig. 4 is a perspective view showing connection to the weft fork carrier.

Fig. 5. Side elevation partly in section of the attachment.

Fig. 6 is a plan of same.

Fig. 7 is a side elevation of same.

A casing A is affixed by brackets A¹ to the breast beam X of the loom being bolted to the brackets by bolts a⁴ passing through slots a⁵ in the casing to allow of adjustment of the latter.

A coarse pitched screw spindle B is mounted on bearings in the casing A and carries a nut C to which is connected an upwardly projecting rod C¹ which projects through a slot a in a slide A² mounted on the top of the casing A so that it can slide thereon. The slide is formed with a longitudinal slot a in which is mounted an adjustable stop C² which is engaged by the vertical arm C¹ after the nut C has moved a predetermined distance along the screw B.

A friction wheel D is mounted on one end of the screw B and engages with and is driven by a wheel D¹ mounted on the end of the taking up roller X¹ of the loom. The wheel D¹ on the taking up roller is preferably grooved and the periphery of the wheel D is shaped to fit into the groove of the wheel D¹.

An arm or projection E is mounted on the top or slide A² and is connected to the weft fork carrier X² by a flexible connection such as the cord E¹ so that when the rod C¹ comes in contact with the stop C² and causes the slide A² to move with it the cord E¹ will be tightened and any further movement will cause the weft fork to remain in the path of the weft hammer X³ and consequently the weft lever X⁴ will be operated to stop the loom.

The end of the screwed spindle B carrying the friction wheel D is mounted in a bearing b² which can slide in a slot a² in the end of a casing A. The bearing b² is affixed to a rod F projecting upwardly through a slot a³ in the end of the slide A². A coil spring f³ around the upper part of the rod F tends to raise the latter and with it the

bearing b^2 and the end of the screwed spindle B.

A lever G is bolted at one end of the weft lever X⁴ and at the other end bears on a knob f at the upper end of the rod F during running of the loom. The pressure of this lever G is sufficient to overcome the upward pressure of the spring f³ so that the bearing b² is pressed downwards and the friction wheel D is pressed against the friction wheel D¹ with sufficient force to be driven thereby. When the weft lever has been operated to stop the loom, the end g¹ of the lever G slides off the knob f and the spring F¹ lifts the rod F and the bearing b² so that there is no pressure between the wheel D and the wheel D¹.

One end of a spring F¹ is attached to the end of the screwed spindle B and the other end is affixed to the casing A so that as the spindle B rotates the spring F¹ will tighten up. When the loom is stopped and the pressure between the friction wheels D and D¹ is removed the spring F¹ will automatically rotate the spindle B in the reverse direction to return the nut C to its initial position.

What I claim as my invention and desire to protect by Letters Patent is:—

A stop motion for looms for weaving comprising the combination with the weft fork carrier, weft fork, weft hammer, weft lever and taking up roller of the loom of a friction wheel mounted on the end of the taking up roller, a second friction wheel engaging with the first friction wheel, a coarse pitched screw on the end of which the second friction wheel is mounted, a nut mounted on the screw so that as the latter rotates the nut will travel along it, a projecting rod carried by the nut, a sliding member having a slot in which the projecting rod passes, a stop adjustable in said slot and adapted to be engaged by the rod on the nut, a projection on the sliding member, a flexible connection between the projection on the sliding member and the weft fork carrier so that when the nut has traversed along the screw a distance to bring the rod into engagement with the adjustable stop the sliding member will be moved and tighten the flexible connection, the weft fork carrier will be prevented from moving and the weft fork will remain in the path of the weft hammer and the weft lever consequently can be operated to stop the loom, a bearing in which the end of the screw is carried, a vertical rod affixed to the bearing, a spring acting to raise the rod, a lever affixed to the weft fork lever and bearing against the top of the rod when the loom is running to keep the rod depressed and the bearing in such position that friction wheel on the end of the screw is pressed against the friction wheel on the end of the taking up roller, a spring one end of which is affixed to the screw and the other end of which is anchored to a stationary part of the loom so

that as the screw rotates the spring will be coiled up and when the weft fork lever is moved to stop the loom and the lever affixed to the weft fork lever moved away from the vertical rod the spring controlling the latter will cause the bearing of the screw to lift and the pressure between the two friction wheels to be removed so that the tension in the coiled spring will rotate the screw in the backward direction and the nut will return to its starting position.

In testimony whereof I have hereunto set my hand.

THOMAS PILLING.
